CERTIFICATE OF CORRECTION

PATENT NO. : Des. 532,088 S
APPLICATION NO. : 29/238297
DATED : November 14, 2006
INVENTOR(S) : Sadler

Page 1 of 9

It is certified that error appears in the above-identified patent and that said Letters Patent is hereby corrected as shown below:

Title page, showing an illustrative figure, should be deleted and substitute therefore the attached title page.

Delete the drawing sheets containing figures 1 thru 7 and substitute therefore the attached sheets containing figures 1 thru 7

Signed and Sealed this

Eighth Day of April, 2008

JON W. DUDAS
Director of the United States Patent and Trademark Office
